UNITED STATES PATENT OFFICE.

ANDREW RUMPLER, OF CUDAHY, WISCONSIN.

WINDOW.

Application filed October 23, 1924. Serial No. 745,330.

My invention relates to improvements in windows.

In a companion application bearing even date herewith, I have shown and described a building wall peculiarly adapted for heat insulation in the construction of inexpensive dwellings and other buildings, the body of the wall being composed of a block of earth having a clay or fibrous binder and kept dry by inner and outer facing walls.

The object of my invention is to provide a window structure especially adapted for use in buildings having walls of the type described in said companion application, although also adapted for use in any building.

More particularly stated, it is an object of my invention to provide a duplex window structure having outer windows hinged to the window frame or casing, and inner windows which can be removed from the inside and window screens substituted.

A further object of my invention is to provide a ventilating window in which adequate ventilation may be secured without opening the main sash and in which the several windows of a set will be formed for mutual weatherproof engagement, and will be so constructed that even when the special ventilating window is open no ordinary storms will result in the entry of rain or snow through the ventilating window or through the remaining windows of the group.

In the drawings:

Figure 1 is a perspective view of a window and window frame embodying my invention.

Figure 2 is a sectional view drawn in line 2—2 of Figure 1.

Figure 3 is a vertical sectional view drawn in line 3—3 of Figure 1.

Figure 4 is a view similar to Figure 3, illustrating an embodiment of this invention slightly modified from the Figure 3 disclosure.

Fig. 5 is an enlarged detail view illustrating a further modification and taken on substantially the section of Figure 4.

Like parts are identified by the same reference characters throughout the several views.

Referring to Figure 2, the studs 1 and 2 of the building wall support inner and outer facings 3 and 4, respectively. Between the studs and between these facings there is a solid wall 5 separated from the studs and

facings by air spaces 6, as fully set forth and described in said companion application. The window casing members 7 are applied directly to the studs 1 and 2, and the casing boards 8 are applied to the inner and outer surfaces of the walls with their margins overlapping the casing members 7. The window openings formed by the casing members 7 are sub-divided by a cross piece 10 preferably located about two-thirds of the distance from the bottom to the top of the casing, leaving a major window opening to be normally closed by the window sash 11 and insertable from the interior against suitable stops 12 affixed to the window frame 14. The upper opening may be similarly closed by a sash 15 fitted to stops 16 secured to the upper window frame 17. Normally, however, a screen 18 will be secured to the sash 15 instead of glass.

An outer window sash 19 is hinged along its upper margin to the window frame or casing and adapted to be swung upwardly to the position in which it is shown in Figure 1 when weather conditions permit, whereby ventilation is permitted through the screen 18. This sash 19 may be supported in the raised position by ordinary folding braces or brace hooks 20. This sash 19 when closed preferably abuts the outer margins of the window frame 17.

The lower window opening may be closed by a pair of outer sashes 21, having side margins 22 hinged at 23 to the respective sides of the window casing, whereby these sashes may be swung laterally about the vertical axes of the hinge pintles and held by braces 24. When closed, the swinging side margins of these sashes are brought into abutting contact. Each of these sashes preferably carries a single glass panel 25 and forms an outer or storm window. The sashes 21 preferably close against the outer margins of the window frame members 14 and are, of course, spaced from the inner sash. The inner sash 11, and also the upper sash 15, may be secured in position by any suitable fastenings 26 which may be quickly adjusted to position of release to allow the removal of the associated inner sash. The fastenings 26 preferably comprise spring-actuated locking bolts of ordinary type which pass through apertures in the sash and enter sockets in the window frame.

When these locking bolts are retracted and the inner sash removed, the outer sash may

- be quickly adjusted to open or closed position after which the inner sash may be replaced. The quick detachable characteristic of the inner sashes 11 and 15, and the fact 5 that these sashes may be removed and replaced from the interior, facilitates the substitution of sash provided with wire screens for sash provided with glass whenever such substitution is desired. When screen sashes 10 are employed it is not necessary to replace them with glass in case of a storm, since the outer sashes 19 and 21 may be quickly closed. The lower screen sash will, however, be replaced with glass-carrying sash during cold 15 weather, and in extremely cold weather the upper sash 15 may also be replaced with sash provided with a glass panel, if desired.
- In the Figure 4 construction the ventilating sash 19 is set inside the frame member 20 28, and the frame member is finished at its lower margin 29 at a 45° angle, whereby to limit the outward and upward swinging movement of the sash. The arrangement is such that whether the sash is open or closed, 25 water striking the frame member 28 will be directed outwardly of the sash and will not find access through the crack between the sash and the member to which it is pivoted.
- 30 In this preferred construction the lower rail 30 of the ventilating sash 19 is preferably beveled as indicated, and the upper margins 31 of sash 21 are likewise formed with a bevel complementary to the bevel of sash rail 30. Thus, when the sashes 21 are 35 closed, sashes 19 may be closed above them to interact with each to produce a storm-proof joint. If desired, the beveled rail 31 of sash 21 may include a portion at substantially 40 45 degrees to mate with rail 30 of sash 19, and may also include a portion at an angle of substantially 30 degrees, as indicated in Figure 5. This permits the use of a strip of flashing 32 seating on frame member 10 and provided with a projecting portion 33 so positioned as to permit sash 21 to be opened and nevertheless to direct water outwardly over said sash so that no 45 leakage will occur even when the ventilating sash 19 is elevated to the position in which it appears in Figure 4. When sash 19 is so elevated, rain may conceivably drive about the lower margin or margins of said sash and may reach frame member 10. In such an event, however, the flashing 32 will receive the water and will ensure that it does not seep past the upper margins of sash rail 31 toward the interior of the building.
- 50 By way of further ensuring a stormproof construction I prefer to construct frame member 35 integrally with a shoulder at 36, and with an outwardly and downwardly tapering wall 37. The length of sash 21 is such that it will seat against shoulder 36

when the sash is closed, thus ensuring that no moisture can drive past the lower margin of said sash beneath frame member 14' of the frame 14.

I claim:

1. The combination with a window casing, of a window frame within said casing and intermediate the margins thereof, a window sash filling said frame and removably insertable from the interior of said casing, and an outer window sash hinged to the outer margin of said casing and flush therewith when in closed position, said frame having its outer margins in abutting relation to said outer sash when said outer sash is in 70 closed relation.
2. The combination with a window frame and casing, of a division member extending across the window frame above the horizontal center line thereof, window sashes removably insertable from the interior and adapted to fill said window frame above and below said division member, an outer window sash hinged to the upper margin of 75 said window casing for swinging movement 80 into abutting contact with the exterior margin of said window frame to close said frame above said division member, whereby it may be swung outwardly and upwardly from 85 closed position, and a pair of outer window 90 sashes in hinged connection with the side margins of the frame for swinging movement into abutting contact with the exterior margin of said window frame to close said 95 frame below said division member.
3. In combination with a window casing, a window frame fitted within said casing intermediate the margins thereof and subdivided into upper and lower window openings by a horizontal cross piece, window and screen sashes removably fitted within their respective window openings, an upper outer sash hinged at the top of said window casing 100 for closing said upper opening and to swing 105 in a vertical plane, and lower outer sashes each hinged at a corresponding side of said window casing for closing said lower window opening and adapted to swing laterally 110 in a horizontal plane.
4. The combination with a window frame 115 having a horizontal cross member provided with an outwardly projecting margin having a downwardly and outwardly inclined face, of a lower outer sash provided with an upper margin inclined downwardly and outwardly from a line rearwardly beneath said projecting margin, and an upper outer sash provided with a lower margin inclined downwardly and outwardly and complementary to said inclined face and a portion 120 of the inclined margin of said lower sash.
5. In a device of the character described, the combination with a ventilating sash pivoted for swinging movement on a horizontal axis, of a frame member overhanging the 125 130

- pivoted margin of said sash, and having its lower margin surfaced at an angle less than 90° from the vertical, whereby to provide a stop for the swinging outward movement 5 of the sash and to deflect rain in any position of said sash.
6. In a device of the character described, the combination with a building wall and a window frame therein, of sash normally disposed in said frame intermediate the thickness of said wall, and secondary sash pivoted to said frame and disposed substantially in the plane of said wall, one of said secondary sash being pivoted at its upper 15 margin to the top of said frame and others of said sash being pivoted at their respective outer vertical margins to said frame, and the lower margin of said first mentioned sash and the upper margins of said last mentioned sash being angularly formed for mutual abutment in a downwardly and outwardly inclined plane.
7. In a device of the character described, the combination with a building wall and a window frame therein, of a plurality of sash in superposed relation in said frame and in substantially the plane of the outside of said wall, said frame and sash being formed to provide a series of water-shedding joints 25 throughout their vertical extent.
8. In a device of the character described, the combination with a window frame having an overhanging member with a beveled lower margin, of a window sash pivoted to the top of said frame immediately adjacent said beveled margin, said margin being adapted to limit the pivotal movement of said sash, and a second sash pivoted for movement in a horizontal plane and imme- 30 diately beneath the first mentioned sash, 40 said first mentioned sash being adapted when closed to overlap the second mentioned sash.
9. In a device of the character described, the combination with a window frame having an overhanging member with a beveled lower margin, of a window sash pivoted to the top of said frame immediately adjacent said beveled margin, said margin being adapted to limit the pivotal movement of 50 said sash, and a second sash pivoted for movement in a horizontal plane and imme- 55 diately beneath the first mentioned sash, 55 said first mentioned sash being adapted when closed to overlap the second men- tioned sash, the lower margin of said first mentioned sash and the upper margin of said last mentioned sash being beveled to provide complementary angles, whereby said first mentioned sash will overlap said second sash while flush therewith.
10. In a device of the character described, the combination with an upwardly swinging sash and a laterally swinging sash, the former being provided with a lower marginal portion beveled in a downwardly and outwardly inclined plane, and the laterally swinging sash having its upper margin finished to provide a beveled portion comple- 65 mentary to the beveled margin of the first mentioned sash and having an inner marginal portion at less of an angle from the horizontal, together with a frame member forming an abutment for said laterally swinging sash and provided with flashing overhang- 70 ing said last mentioned marginal portion thereof substantially as disclosed herein.
